UNITED STATES PATENT OFFICE.

ALBERT N. LATTIN, OF BROOKLYN, NEW YORK, ASSIGNOR TO S. STERNAU & COMPANY, OF BROOKLYN, NEW YORK, A FIRM.

DESIGN FOR A BATH-ROOM HOOK.

No. 38,025.

Specification for Design.

Patented May 22, 1906.

Application filed April 6, 1906. Serial No. 310,386. Term of patent 7 years.

To all whom it may concern:

Be it known that I, ALBERT N. LATTIN, a citizen of the United States, residing in Brooklyn, in the county of Kings, State of New York, have invented a new, original, and ornamental Design for a Bath-Room Hook, of which the following is a specification, reference being made to the accompanying drawing, forming a part hereof.

The figure shows a perspective view of a bath-room hook, showing my new design.

I claim—

The ornamental design for a bath-room hook, as shown.

ALBERT N. LATTIN.
